ARTIFICIAL LIMB KNEE JOINT

Clarence A. Renfro, San Diego, Calif.

Application August 21, 1948, Serial No. 45,541

1 Claim. (Cl. 3—2)

1

My invention relates to an artificial limb knee joint, and the objects of my invention are:

First, to provide a joint of this class in which substantially automatic spring-loaded forward return of the shin joint of an artificial limb is accomplished during the walking motion of the wearer, which forward motion may be regulated according to the speed required by the wearer directly proportioned to his stride;

Second, to provide an artificial limb knee joint in which spring-loaded forward motion of the shin joint is modified by an adjustable friction collar, which directly regulates the speed of return of said shin joint, whereby shock of abutment of the shin joint at its forward limit of travel is minimized;

Third, to provide an artificial limb knee joint of this class which is very sturdy and is so constructed that the limb hinge bearing is provided with a continuous flexible bushing extending from one side of the upper limb member to the opposite side thereof, greatly increasing stability of the joint, and long-wearing characteristics, in addition to dampening shock stresses transferred to the limb hinge bearing from the foot of the artificial limb;

Fourth, to provide an artificial limb knee joint of this class having automatic spring-loaded means for the forward return of the lower limb when walking, which automatically tends to retract the lower limb when the same is disposed at substantially right angles to the upper limb in sitting position, whereby the lower limb does not tend to move forward from a natural position when the wearer is sitting down;

Fifth, to provide an artificial limb knee joint of this class which is particularly adapted for use in connection with the stump of a limb amputated directly at the knee joint;

Sixth, to provide an artificial limb knee joint of this class which is very light and compact in proportion to its function;

Seventh, to provide an artificial limb knee joint of this class which is particularly adapted for use by persons desiring an end bearing socket fitting; and

Eighth, to provide an artificial limb knee joint of this class which is very simple and economical of construction, efficient in operation, and which will not readily deteriorate or get out of order.

With these and other objects in view, as will appear hereinafter, my invention consists of certain novel features of construction, combination and arrangement of parts and portions, as

2

will be hereinafter described in detail, and particularly set forth in the appended claim, reference being had to the accompanying drawings and to the characters of reference thereon, forming a part of this application, in which:

Fig. 1 is a side elevational view of an artificial limb, showing my artificial limb knee joint in connection therewith; Fig. 2 is a rear view similar to Fig. 1, showing the artificial limb fragmentarily; Fig. 3 is a side elevational view of the knee joint operating mechanism, showing portions broken away and in section to amplify the illustration; Fig. 4 is an enlarged rear elevational view of the operating mechanism shown in Fig. 3 of the drawings; Fig. 5 is a sectional view taken from the line 5—5 of Fig. 4, showing parts and portions in elevation to facilitate the illustration; Fig. 6 is a plan sectional view, taken from the line 6—6 of Fig. 2, showing the structure on an enlarged scale; Fig. 7 is an enlarged fragmentary sectional view taken from the line 7—7 of Fig. 3; and Fig. 8 is an enlarged fragmentary sectional view taken from the line 8—8 of Fig. 1.

Similar characters of reference refer to similar parts and portions throughout the several views of the drawings.

The upper limb member 1, limb shin member 2, limb hinge bearing straps 3 and 4, bearing bolts 5 and 6, leather bushing 7, brackets 8 and 9, plate 10, links 11 and 12, spring 13, friction collar 14, friction adjusting screw 15, screw 16, bolts 17, 18 and 19, and the bearings 20, 21 and 22 constitute the principal parts and portions of my artificial limb knee joint.

The upper limb member 1 is preferably a socket fitting for amputees having either end bearing stubs or those in which part of the weight bearing is around the upper edge of the upper limb member 1. Hinged to the upper limb member 1 by means of the limb hinge bearing straps 3 and 4 and the bearing bolts 5 and 6 is the limb shin member 2. The limb hinge bearing straps 3 and 4 are fixed to opposite sides of the limb shin member 2 and are recessed therein flush with the outer surface thereof. These limb hinge bearings 3 and 4 are substantially identical; therefore, the hinge bearing strap 3 will be hereinafter described. This hinge bearing strap 3 is connected to the upper end of the limb shin member 2 by means of pins 3a. The upper end of this limb hinge bearing strap 3 is provided with an arcuate recess 3b therein, in which the head of the bearing bolt 5 is positioned. The head 6a of the bearing bolt 6 is positioned within

the upper end of the limb hinge bearing strap 4, and is provided with an internal bore 6b, screw-threaded on the externally screw-threaded stub 5b of the bolt 5. Thus, the outer surface portions of the bolts 5 and 6 form a smooth continuous bearing for the leather bushing 7, which is a hollow-cylindrical bushing of flexible character, adapted to absorb certain shocks transmitted by the bolts 5 and 6 from the lower shin member 2 during walking of the wearer on my artificial limb knee joint.

As shown in Figs. 2, 3 and 4, the bracket 8 is fixed to the upper limb member 1 by pins 8a, and this bracket 8 is provided with a clevis portion 8b in which the normally upper end of the link 11 is pivotally mounted by means of the bolt 19. The normally lower end of the link 11 is pivotally connected with the link 12 by means of the bolt 17, and the normally lower end of the link 12 is pivotally connected to the bracket 9 by means of the bolt 18, all as shown best in Fig. 3 of the drawings. The bracket 9 is connected to the frontal portion of the limb shin member 2 by means of the plate 10 engaging the outer side thereof, with which the screws 18a are connected, and extending into screw-threaded relationship with the bracket 9, forming a rigid anchor for the bolt 18, on which the link 12 is pivotally mounted.

The bearings 20, 21 and 22 are ball bearings, shown best in detail in Fig. 5 of the drawings, which greatly reduce frictional loss in the pivotal operation of the links 11 and 12, all as shown best in Fig. 3 of the drawings, it being noted that the bearing 20 is positioned on the bolt 17, the bearing 21 on the bolt 18, and the bearing 22 on the bolt 19.

The friction collar 14 is provided with a hollow cylindrical portion 14a, which snugly fits a laterally-extending cylindrical trunnion 12a of the link 12, and this friction collar 14 is provided with slotted lugs 14b, relieved to the central bore of the collar 14, as shown best in Fig. 3 of the drawings. The friction adjusting screw 15 passes through the lugs 14b and tends to clamp the cylindrical portion 14a of the collar 14 around the trunnion portion 12a of the link 12 for regulating the frictional drag of the link 12 relatively to the link 11, it being noted that the friction adjusting collar is provided with the lugs 14c and 14d engaging opposite sides of the link 11, while the screw 15 is screw-threaded in the link 11 and holds the friction adjusting collar rigidly connected to the link 11. It will be noted that the friction adjusting screw 15 is screw-threaded in the individual lug 14e and the opposite lug of the collar 14 is free longitudinally of the screw 15, permitting the lugs 14b and 14e to be forced toward each other for tightening the collar 14 around the trunnion 12a.

The helical spring 13 is connected at its one end 13a to a boss 11a by a screw 11b. The helical body 13c of this spring 13 is wound around the extending trunnion 12b of the link 12, and the opposite end 13b of the spring 13 from the end 13a engages the normally upper side of the link 12, as shown best in Fig. 3 of the drawings. The link 11, intermediate its ends, is provided with a bumper plate 11c, engageable with a bumper pad 1a at the rear of the upper limb member 1, at its lower extremity. This bumper pad 1a acts as a forward stop for the pivotal movement of the limb shin member 2 relatively to the upper limb member 1.

The operation of my artificial limb knee joint is substantially as follows: When the wearer of

my artificial limb knee joint is walking, the spring 13 tends to force the bolt 17, connecting the links 11 and 12, toward the frontal portion of the knee joint, which acts about the axis of the bolts 5 and 6, tending to force the limb shin member 2 forwardly. Thus, each time a step has been completed and the artificial limb is raised, the spring 13 pivots the lower shin member 2 forwardly for the beginning of another step. The forward speed of the limb shin member 2 forwardly when urged by the spring 13 is regulated by the friction collar 14, frictionally adjustable on the trunnion 12a of the link 12 by means of the friction adjusting screw 15. Tightening or loosening of this friction adjusting screw 15 results in slower or faster forward motion of the limb shin member 2 forwardly, as desired. Thus, the friction adjusting screw permits the regulation of the forward movement of the limb shin member 2, in accordance with the stride of the wearer, so that a direct synchronism with the normal limb of the wearer may be made, so that the movements of the artificial limb closely simulate the normal limb.

When the wearer of my artificial limb knee joint sits down, the bracket 8 is forced into the dash line position as shown in Fig. 3 of the drawings, wherein the bolt 19 passes over center of the axis of the bolts 5 and 6, causing the spring 13 to create backward pivotal tension of the limb shin member 2, tending to retract the same instead of forcing the same forwardly, which is normal to the standing position, as shown by the solid lines, in Fig. 3 of the drawings.

It will be noted that the bumper pad 1a engaging the bumper plate 11c provides a cushion stop for the limb shin member 2 when pivoted forwardly by means of the spring 13 about the axis of the bolts 5 and 6. The frictional operation of the friction collar 14 on the trunnion 12a of the link 12 provides for deceleration of the limb shin member 2 in its forward swinging motion about the axis of the bolts 5 and 6, as the plate 11c of the link 11 approaches the pad 1a in connection with the upper limb member 1. This deceleration accompanies progressive relaxation of the spring 13, the tension of which lessens slightly proportionately progressive to the forward pivotal movement of the limb shin member 2 about the axis of the bolts 5 and 6. As hereinbefore described, the leather bushing 7 provides a flexible, yieldable bearing for the bolts 5 and 6, on which the limb hinge bearing straps 3 and 4 are mounted, it being noted that the straps 3 and 4 pivot on the bolts 5 and 6, respectively, and that the leather bushing 7 does not bear any frictional load or wear occasioned by the pivotal movement of the limb shin member 2 relatively to the upper limb member 1.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claim.

Having thus described my invention, what I claim as new and desire to secure by Letters Patent is:

In an artificial limb knee joint of the class described, an upper limb member, a lower limb member, a bracket fixed to said upper limb member, a bracket fixed to said lower limb member, a link pivoted to the bracket in connection with

said upper limb member, a second link pivoted in connection with the bracket secured to said lower limb member, the opposite ends of said links from said brackets pivotally connected together, and spring means tending to pivot the lower limb member forwardly relatively to the upper limb member, said spring means acting around the axis of the pivotal connection of said links, an adjustable collar, said link pivotally connected to the bracket secured to the lower limb member having a protruding portion upon which said adjustable collar is closely fitted, said adjustable collar rigidly connected with the link pivoted to the bracket secured on said upper limb member, said collar being split at one side and a friction 15 adjusting screw arranged to tighten said collar on said trunnion, whereby action of said spring may

be modified, permitting said lower limb member to pivot relatively to said upper limb member urged by said spring at a slower or faster rate, as desired.
